[57] ABSTRACT

Apparatus for laterally transposing a load relative to its path of travel, such as a motor vehicle, including a plate disposed atop a transversely movable carriage which is biased to a central position for simultaneously receiving laterally adjacent wheels of the load, and outwardly divergent guide rails which extend across the plate to engage the load such that the load is laterally transposed to a preselected position as it moves across the plate.

LOAD SHIFTING APPARATUS

BACKGROUND OF THE INVENTION

1. Field of the Invention

The present invention pertains to load shifting apparatus and more particularly to such apparatus for transposing a moving load to a preselected lateral position relative to its path of travel.

2. Description of the Prior Art

A number of techniques have been devised in the past to assist an operator in properly aligning a rolling load to a preselected lateral position. Such techniques typically employ aligning markers, guide rails, and the like and have not proven to be entirely satisfactory since alignment of the load by using such devices remains primarily dependent upon the judgement of the operator and is thus often subject to error.

The prior art is generally cognizant of apparatus for laterally aligning or transposing a rolling load independently of the steering thereof by the operator and which have attempted to overcome the above problems. Such attempts, however, have typically resulted in devices which are mechanically complex and relatively expensive and are therefore often commercially unacceptable.

SUMMARY OF THE INVENTION

The present invention is summarized in apparatus for laterally transposing a moving load relative to its path of travel including a housing having an open upper end, a set of parallel tracks in the housing, a carriage assembly including a frame having upper and lower portions and including a set of wheels journaled on the lower portion, a plate fixedly attached to the upper portion of the carriage assembly and covering the open upper end of the housing for receiving the moving load, spaced guide members extending across the housing and adapted to engage the moving load for laterally guiding the same, and a pair of spaced springs each disposed between the carriage assembly and the housing and biasing the carriage assembly to a central position therein.

An object of the present invention is to construct a load transfer apparatus having a transversely movable plate cooperating with guide members for laterally transposing a load to a preselected position.

The present invention has a further object in that load shifting apparatus includes a movable carriage assembly biased to a central position by a pair of spaced springs.

Another object of the present invention is to construct a carriage assembly including a set of wheels which cooperate with a pair of tracks to transversely shift a moving load as it moves thereacross.

Some of the advantages of the present invention over the prior art reside in the ability to laterally align a load independently of the steering thereof by the operator, economy of manufacture, simplicity of installation and reliability in operation.

Further objects and advantages of the present invention will become apparent from the following description of the preferred embodiment when taken in conjunction with the accompanying drawings.

BRIEF DESCRIPTION OF THE DRAWINGS

FIG. 1 is a front perspective view partly broken away of a preferred embodiment of transposing apparatus according to the present invention;

FIG. 2 is a sectional view taken along line 2-2 of FIG. 1;

FIG. 3 is a plan view partly broken away of the apparatus of FIG. 1; and

FIG. 4 is a sectional view taken along line 4-4 of FIG. 3.

DESCRIPTION OF THE PREFERRED EMBODIMENT

A preferred embodiment of transposing apparatus according to the present invention is illustrated in FIGS. 1 through 4 and includes a generally rectangular housing 18 having parallel end walls 20 and 22 interconnected with parallel side walls 24 and 26, respectively, the walls being bent outwardly at their upper edges to form flanges 28, 30, 32 and 34, respectively. A set of spaced support members 36 extend across the open lower end of housing 18 parallel to side walls 24 and 26 and are preferably attached as by welding to spaced points along the bottom edge of walls 24 and 26 of the housing. It is noted that a flat rectangular plate extending completely across the bottom of housing 18 may be utilized in place of support members 36 depending upon the particular installation contemplated.

As illustrated in FIGS. 1 and 2, housing 18 is adapted to be recessed within a rectangular pit formed in the ground 10 with flanges 28, 30, 32 and 34 mounted flush with the surface. It should be understood, of course, that housing 18 may be mounted in place by any suitable technique; for example, it may be set into a properly sized preformed concrete pit or may be placed into a hole dug to the proper depth, after which the sides of the hole may be filled in and the top surface suitably paved. In addition, the bottom of the pit may be slightly sloped and may include a conventional drain connection preventing the collection of water within the housing.

A pair of elongated spaced rods 38 and 40 having an inverted, generally U-shaped cross-section extend across the bottom of the housing 18 in parallel alignment with side walls 24 and 26 and are fixedly attached to the top surface of support members 36. Rods 38 and 40 support a respective one of a pair of parallel tracks 42 and 44 which are rigidly affixed to the top surfaces thereof as shown in FIG. 2. A pair of stops 46 having a generally L-shaped cross-section are horizontally mounted within housing 18 and extend between side walls 24 and 26 adjacent the ends of tracks 42 and 44. Stops 46 may be held in place against walls 24 and 26 by any suitable means such as welding. The ends of housing 18 are covered by a pair of flat plates 47 which are hingedly mounted to end walls 20 and 22 to provide access to the interior of the housing after installation. A pair of shims 48 are mounted atop flanges 32 and 34 at each end of housing 18 so as to separate the distal ends of plates 47 from the upper edge of stops 46 as can be seen in FIG. 4.

A carriage assembly, indicated generally at 50, is adapted to ride upon tracks 42 and 44 and includes spaced parallel U-shaped side channels 52 and 54 interconnected at their ends with spaced parallel U-shaped end channels 56 and 58 to form a rigid rectangular

frame. Mounted at each of the corners of the rectangular frame is a respective one of a set of identical vertically disposed U-shaped corner channels 60 which laterally extend from channels 52 and 54. The carriage 50 further includes two side wheel assemblies 62 and 64, each having first and second wheels 66-68 and 70-72 mounted upon the ends of a shaft 74-76 which is journaled through the approximate center of corner channels 60 in a lower portion of carriage 50 for rotation therein. Wheels 66, 68, 70 and 72 are similar in construction and are generally cylindrical with a semicircular groove running centrally around the peripheral surface thereof for cooperation with tracks 42 and 44. Wheels 66, 68, 70 and 72 maintain the carriage assembly upon the tracks and, at the same time, enable free movement of the carriage longitudinally therealong.

A pair of compression springs 78 and 80 are mounted in opposite corners of housing 18 between a respective upright wall of stops 46 and the upper portion of an outer flange of U-shaped corner channels 60 of carriage assembly 50. Springs 78 and 80 may be mounted by any suitable means and may each, for example, have axially projecting ends which are disposed within suitable holes in corner channels 60 and stops 46 of the housing, as illustrated.

A flat rectangular top plate 82 is centrally disposed atop carriage assembly 50 and is fixedly attached to an upper portion thereof by any suitable means such as bolts, welding, or the like. The shorter dimension of top plate 82 is slightly less than the shorter inner dimension of housing 18 to provide a flush fit therewith, as can best be seen in FIG. 2, and its longer dimension is sufficiently larger than the open area between stops 46 of housing 18 such that the housing is always completely covered by the top plate.

A pair of longitudinally aligned spaced guide rails 84 and 86 extend completely across the shorter dimension of housing 18 adjacent an end thereof as illustrated in FIG. 1. Each of the guide rails 84 and 86 is in the form of an inverted generally U-shaped pipe having an upright vertical rear leg and an angularly disposed front leg interconnected by a horizontal top bar. Each rail is mounted with the front and rear legs thereof firmly supported within the ground in front of and behind the housing 18. The horizontal bar of each guide rail is bent to form an obtuse angle in a horizontal plane adjacent its rear leg such that both rails diverge outwardly toward the front of the housing 18 for cooperation with a side wheel of a vehicle. It should be appreciated that the particular construction and shape of rails 84 and 86 is dependent upon the nature of the moving load for which the apparatus is designed and is described herein for use in connection with a moving vehicle for illustrative purposes only.

Before discussing the operation of the present invention, it is important to keep in mind that proper alignment of a moving load is necessary in a number of diverse applications such as on automated or semiautomated production lines, in connection with truck loading and unloading docks, and in conjunction with vehicle washing installations, to name but a few. In such applications, it is desirable that alignment of the load be effectively attained on an uninterrupted basis by a simple and relatively maintenance free apparatus. While the present invention has a number of uses, its operation will be described herein in connection with its use with a motor vehicle solely for purposes of illustration.

Prior to advancement of a vehicle onto the transposing apparatus of the present invention, carriage assembly 50 which carries top plate 82 is centrally biased by springs 78 and 80 to its neutral position within housing 18 as shown in FIGS. 3 and 4. Compression springs 78 and 80 permit the top plate and carriage assembly to move transversely of the vehicle path of travel and serve to rapidly reposition the top plate to its neutral position after each set of wheels pass off the rear edge 10 of the plate 82.

With the top plate 82 and carriage assembly 50 in their neutral position, the present apparatus is ready to receive the front set of laterally adjacent wheels of a vehicle. As the vehicle is driven toward the transposing apparatus, it is approximately aligned for entry by the driver and as it continues to move forward, will ride onto top plate 82. As the vehicle rides onto the top plate, both front wheels will be simultaneously received thereby such that the front of the vehicle may be laterally moved upon the track supported carriage assembly 50. If the vehicle has been properly aligned by the driver, the top plate 82 will remain in its neutral position under the biasing force exerted by springs 78 and 80 as the vehicle moves forward, and as the front 20 wheels of the vehicle roll off the rear edge of top plate 82, the left front wheel will pass between guide rails 84 and 86.

If on the other hand, the front of the vehicle is too far to the left (as visualized in FIG. 1), the left front wheel 30 will rub against guide rail 84 as the vehicle moves across plate 82. Because of the angular configuration of guide rail 84, a force will be exerted on the left wheel tending to move the front of the vehicle to the right. Since both front wheels of the vehicle are supported atop plate 82 at this time and since the top plate and carriage assembly 50 are transversely movable along tracks 42 and 44, the front of the vehicle as well as top plate 82 and carriage assembly 50 will move to the right as the left wheel rubs against guide rail 84. In this manner, the front of the vehicle will be gradually shifted to the right as it moves forward until it is properly aligned whereupon the front wheels will ride off the rear edge of plate 82.

A similar operation results if the vehicle is too far to the right as it traverses plate 82. In that case, the left front wheel would contact and rub against the right guide rail 86 causing a force to be applied to the front of the vehicle tending to move it and the carriage assembly to the left as the vehicle moves forward. As before, the front of the vehicle will continue to be moved to the left upon top plate 82 and carriage assembly 50 until it is properly aligned to the preselected desired position.

As the front wheels of the vehicle pass off the rear plate 82, the carriage assembly 50 will be returned to its neutral position by springs 78 and 80 whereupon the rear of the vehicle may be aligned in the same manner as described above.

It can thus be seen that a vehicle or other moving load will be simply and effectively shifted in a lateral direction by the apparatus of the present invention and that such alignment is independent of the steering or initial direction of the load. Therefore, proper alignment of the load can be assured without having to rely upon the judgement of an operator. As a result, vehicle washing installations, for example, which are equipped with apparatus according to the present invention are

more attractive to the public since the vehicle driver need not be concerned with having to properly align his vehicle, and the washing installation owner need not provide an attendant to direct or guide the vehicles to be washed into the washing apparatus. It should be reiterated that the present invention is adaptable for use not only with a vehicle washing installation but also with truck loading docks, assembly lines, and wherever it is desired to laterally shift a moving load into a particular alignment.

Inasmuch as the present invention is subject to many modifications, variations and changes in detail, it is intended that all matter contained in the foregoing description or shown in the accompanying drawings shall be interpreted as illustrative and not in a limiting sense. 15

What is claimed is:

1. Apparatus for laterally transposing a moving load relative to a linear path of travel comprising, in combination:

housing means having an open upper portion substantially flush with said path of travel and extending transversely thereto, said housing means including a pair of spaced parallel side walls interconnected with a pair of spaced parallel end walls to form an open rectangular enclosure, each of said walls having an integral flange on an upper edge thereof extending outwardly normal to said walls, and a plurality of spaced support members extending transversely under said housing means;

a pair of spaced parallel tracks fixed to said support members extending longitudinally of said housing means;

a carriage assembly including a pair of spaced side frame members interconnected at their ends by a pair of end frame members to form an open rectangular box, a pair of shafts each journaled through

the side frame members at the ends thereof, a wheel mounted on each end of each of said shafts, each said wheel having a peripheral profile adapted to engage said tracks;

a pair of stop members each fixedly attached to said housing means adjacent a respective end of said tracks to limit movement of said carriage assembly therealong;

a support plate fixedly superimposed on said carriage assembly and being dimensioned so as to be received in the open upper portion of said housing means in substantially flush relation with said path of travel, end edges on said support plate being spaced from the respective end walls of said housing means to leave a space between each end edge and the respective end wall of said housing means when said carriage assembly is substantially centered in said housing means,

a pair of cover plates disposed adjacent the end walls of said housing means, each cover plate being hingedly attached to the respective end wall of said housing means and normally extending thereover to cover portions of said support plate adjacent the respective end edge thereof regardless of the positioning of said carriage assembly;

guide means adapted to engage the moving load for laterally guiding the same and including a pair of spaced guide rails fixed across said housing means and having an initial converging portion integral with a parallel terminal portion; and

a pair of coil springs each mounted in compression between an end of said carriage assembly and the adjacent end wall of said housing means, said springs biasing said carriage assembly to a central position in said housing means.
